ABSTRACT: A heat exchanger mounting base and a heat exchanger assembly for use with and in combination with a gas compressor for defining an improved inter- and after-cooler configuration. The base comprises upper and lower mounting surfaces; upper surfaces are provided for mounting a plurality

of heat exchanger units. The lower, ported surface accommodates the transfer of gas to and from a compressor stage housing. Ducting formed within the base accommodates the transfer of gas from a given exhaust port of the compressor to the inter-cooler stage and therefrom to a second stage of the compressor. The base accommodates the transfer of gas from the second stage of the compressor through several passes of a second heat exchanger unit. The heat exchanger units are mounted in spaced relationship upon the base and, with end walls, define a chamber therewith. Grille work mounted on the outer surfaces of the heat exchanger units accommodates for the influx of coolant air through both heat exchanger units simultaneously and an updraft of the coolant air to an exhaust plenum. The cooling air is forced to flow through the grille work, and the chamber subsisting between the heat exchanger units, by means of a single fan motor mounted above the chamber. A manifold, comprising one of the end walls of the chamber has a plurality of apertures formed therethrough. One of the apertures accommodates for the inflow of a compressed gas product, from a first stage of the compressor, for communication therefrom through the base member to a first of the heat exchanger units. The other aperture in the manifold is provided for exhausting cooling air from the first stage of the compressor for the venting thereof through the chamber. Finally, there is an aperture provided in the base member for the conduct of cooling air from the second stage of the compressor for passage into the chamber and for exhausting thereof therefrom.

HEAT EXCHANGER MOUNTING BASE AND HEAT EXCHANGER ASSEMBLY

This invention pertains to heat exchanger unit mounting bases and heat exchanger assemblies for use with, and in combination with, gas compressors having external gas ports, and especially to such a base and assembly as obviate any requirement for external piping or conduits for interconnecting the gas compressor with the heat exchanger units.

In the prior art it has been necessary to mount heat exchanger units, for intercooler and aftercooler use with a gas compressor having a plurality of stages, with external piping or conduits. Also, in the prior art, it is customary for each heat exchanger unit to have its own separate and distinct means for passing coolant medium therethrough.

It is an object of this invention to teach a mounting base for at least one heat exchanger unit which eliminates any necessity for external piping or conduit arrangements, the mounting base having means for accommodating such one heat exchanger unit thereon, and means for accommodating an abutting engagement of the mounting base with an external wall of a given gas compressor, with means for admitting gas into the base and therefrom directly into and through the external wall of the gas compressor through a given gas port of the gas compressor.

It is another object of this invention to teach a novel heat exchanger assembly, for use with a gas compressor having external ports, which incorporates a mounting base, of the type just noted, on which are mounted a plurality of heat exchanger units. The heat exchanger units are mounted on the base in spaced relationship and walls mounted to both the units and the mounting base cooperate to define a chamber through which other single means force a cooling medium through all of the units simultaneously.

A teaching of this invention comprises the provisioning of a base member having upper and lower mounting surfaces. The upper surface is especially configured to accommodate an abutting engagement thereof with heat exchanger units, to facilitate the mounting of such units thereon. Further, the upper surface has openings to accommodate the flow of the gas into and out of the heat exchanger units, and the openings further provide for the transfer of the gas to and from any gas compressor mounted to the lower surface of the mounting base.

Another feature of the invention, which is exemplified by the heat exchanger assembly embodiment disclosed herein by way of example, teaches the use of a manifold as one of the wall means defining the chamber between the heat exchanger units. The manifold is ported to accommodate the influx of the gas product from one stage of any gas compressor abutting engaged with the manifold, and has channeling to facilitate the transfer of the product gas into and out of a plurality of heat exchanger units mounted to the base. Further objects and features of this invention will become more apparent by reference to the following description taken in conjunction with the accompanying figures in which:

FIG. 1 is a side elevation of the assembly of FIG. 2 shown operatively mounted to first and second stage housings of a gas compressor;

FIG. 2 is an isometric view, partly in section, of an embodiment of a heat exchanger assembly according to the invention, with the coolant outlet vent shown in light, broken line;

FIG. 3 is a fragmentary view of the bottom of the mounting base, taken along section 3-3 of FIG. 1, showing the gas ports and the stage-housing coolant apertures; and

FIG. 4 is a diagrammatic illustration of the aftercooler arrangement with the gas flow directions being depicted.

Shown in FIGS. 1 and 2 is a gas compressor 10 comprising a plurality of stage housings 12 and 14 having a heat exchanger assembly 16, according to the invention, abuttingly engaged with and mounted thereto. In this embodiment, the heat exchanger assembly 16 comprises an intercooler 18 and an aftercooler 20. Each cooler comprises a heat exchanger unit 22 mounted to a base member 24 which has a plurality of mounting surfaces 26 and 28. The surface of the base member to

which the heat exchanger units are mounted will be considered the upper surface 26 and the opposite surface therefrom the lower surface 28. The upper surface 26 of the base member 24 has on one side thereof a plurality of elongated openings 30 and 32 to accommodate the entry of the product gas into bank of heat exchanger elements 34 of the one unit for a pass of the gas product therethrough and to accommodate the venting of the now cooled gas from the heat exchanger unit 22 for return into the base member 24. The heat exchanger elements 34 comprise hollow tubing, for the conduct of gas therethrough, which tubing carries spaced-apart annular radiators thereupon. The lower mounting surface 28 of the base member 24 is ported, as shown in FIG. 3, to accommodate the transfer of the now cooled gas product into the second stage of the gas compressor 10. The lower mounting surface 28 is abuttingly engaged with and mounted to a second-stage housing 14 of the gas compressor 10, and a port 36 formed in the lower mounting surface 28 is aligned in juxtaposition with the compressor second stage inlet port, formed in the wall of the compressor second-stage housing 14. Compressed gas product from the second stage is admitted through a second port 38, via the compressor second-stage outlet port aligned therewith, and is conducted through the base member 24 through ducting formed therein into and through the aftercooler heat exchanger unit 20 for cooling and discharge therefrom.

The base member upper mounting surface 26 is angulated at both sides to dispose the heat exchanger units 22 in a "V" configuration. Accordingly the heat exchanger units are spaced apart and cooperate to define, in cooperation with the base member 24, a chamber 40 therebetween. The chamber is further walled in by means disposed at opposite ends of the heat exchanger units, to wit; a cover plate 42 disposed at one end of the heat exchanger units 22 and mounted to the units, and a manifold 44 disposed at and mounted to the opposite ends of the heat exchanger units. An outlet vent 46 surmounts the chamber to provide for an exhaust of the coolant medium therethrough. The outlet vent 46 has mounted therewithin a motorized fan 48 to facilitate the exhausting of the coolant medium, air. The external sidewall of each of the heat exchanger units comprise grilles 70 through which the cooling air can be admitted for passage of the cooling air through the heat exchanger units 22 and for admittance to the chamber 40. The motorized fan 48 updrafts the coolant air from the chamber and vents it out of the upper stack.

It is to be noted, then, that a novel teaching of my invention provides single means, notably the motorized fan 48, to cool a plurality of heat exchanger units 22. The particular arrangement which I teach provides for the simultaneous cooling of both heat exchanger units with the one fan. Also, as is evident in the figures which illustrate an embodiment, the base member 24 to which the heat exchanger units 22 are mounted, in having juxtapositionally aligned openings and porting for the heat exchanger units and gas compressor ports obviates any requirement to provision external piping or conduits to effect the transfer of the product gas from stages of air compressor 10 to the individual heat exchanger units.

The manifold 44 which defines one wall of the chamber 40 has a port 50 which forms an interface with the compressor first stage outlet port 50a, and channelling 52 formed therein which accommodate the discharge of the gas product from the first stage housing 12 of the gas compressor 10 and its transfer to the elongated opening 30 which lies beneath the upper mounting surface 26 of the base member 24 for communication with the interstage or intercooler heat exchanger unit 22; channelling 52 opens at the base or lowermost end thereof on opening 30 to effect this communication.

It is to be noted, from study of FIGS. 2 and 4, that each of the heat exchanger units have returned heads 54 and 56 of different configurations. The return head 54 for the first or intercooler heat exchanger unit is unobstructed. That is, it provides for the unobstructed transverse flow of the product gas thereacross. In the embodiment shown, the product gas makes

a first pass through the first heat exchanger unit 22 to the return head 54, transverses the return head and makes a second pass through this first heat exchanger unit, and flows thence therefrom into the base member 24. The return head 56 for the second or aftercooler heat exchanger unit 22 is partitioned. As shown in FIG. 4, it has a web 58 extending therewithin to effect a different flow of the product gas through the intercooler 22. Product gas is admitted to the aftercooler 20 from the second stage of the gas compressor 10 and is conducted therethrough through a first portion A, of four portions A through D, of the aftercooler, and turned in the return head 56 for a second pass through the second portion B of the aftercooler. The gas is vented from the second portion and turned in a chamber 60 provided in the base member 24 for a third pass through the third portion C of the aftercooler 20, again turned in the return head 56 for a final pass through, the final portion D of the aftercooler. A base member wall 62 separates chamber 60 from other chambers formed in the base member 24 by a further wall 64'. 10 15 20

The product gas which is now fully cooled is conducted through channeling 66 formed in the manifold 44 to the ducted discharge port 68 of the heat exchanger assembly 16. 25

The base member 24 and the manifold 44 each have additional ports 72 and 74, respectively, formed therein for admitting cylinder cooling air into the chamber 40 formed between the heat exchanger units 22. As shown in FIG. 1, each of the air compressor stage housings 12 and 14 have cooling air ports 76. The ports are screened and admit air therethrough for passage along throughways (not shown) within the stage housings to facilitate a cooling of the stage cylinders. The cooling air is exhausted from the stage housings 12 and 14, the housings being gasketed to the manifold 44 and the base member 24 through second screen ports 72a and 74a which are confined within the gasketing (the gasketing not being shown). The cooling air for the first stage compressor cylinders vents through the screened port 74a. This port is in juxtaposition with throughgoing port 74 formed in the rear-most surface of manifold 44 which, in turn, opens on the chamber 40. The other port 72 formed in the lowermost surface of base member 24 is also in juxtaposition with the screened cylinder cooling air port 72a of the second stage housing 14 for conducting the cooling air therethrough also to the chamber 40. Accordingly, ambient air is ingested, by way 45 of screened ports 76, into housings 12 and 14, and is drawn by fan 48 through the ports 72a and 74a. These latter ports, as explained, define interfaces with ports 72 and 74 so as to allow the air to be admitted into chamber 40. Port 72 comprises a throughgoing opening in the lowermost surface of assembly 16, and port 74 comprises a throughgoing opening in the rear-most surface of manifold 44; the two ports 72 and 74, therefore, open internally on chamber 40. With this teaching of my invention, it is required to provide only one motorized fan 48, or like air moving devices, simultaneously to cool both an intercooler and aftercooler and to effect movement of both the first and second-stage cylinder cooling air. All such cooling air is moved into the chamber, and is exhausted therefrom, by such single means. 50 55 60

While I have described my invention in connection with a specific embodiment thereof, it is to be clearly understood that this done only by way of example and not as a limitation to the scope of my invention as set forth in the objects thereof and in the appended claims. 65

I claim:

1. A base for mounting at least one heat exchanger unit, for use with a gas compressor having external gas ports, comprising:

a base member having a plurality of mounting surfaces; 70 wherein:

at least one of said mounting surfaces is configured to accommodate an abutting engagement thereof with at least one given heat exchanger unit, to facilitate a mounting of such one unit thereupon, and 75

a second of said mounting surfaces is configured to accommodate an abutting engagement thereof with an external wall of a given gas compressor, to facilitate a mounting of said base member to such external wall; said base member having

channeling and tube-end means for admitting gas into said base member and for conducting such gas through said one mounting surface for transfer of such gas directly into any such one given heat exchanger unit abuttingly engaged therewith; and

port means for admitting gas from such one unit directly into and through said base member, and through said second surface, for direct transfer of said gas through an external wall of a given, abutting gas compressor via a given gas port of such gas compressor;

wherein said gas admitting means together comprise a plurality of tube-end openings formed in said one surface, and at least one port formed in said second surface, given tube-end openings of said plurality thereof facilitating a conduct of gas into and out of a given heat exchanger unit, and said one port facilitating a conduct of gas to said given gas port of said gas compressor and wherein said base member further includes

at least a second port means for admitting gas directly into said base member from a given, abutting gas compressor, upon such gas issuing from said given compressor through an external wall thereof via a given gas port; and

further tube-end means for directly conducting gas from within said base member through said one mounting surface of said plurality thereof; and

said one mounting surface is further configured to accommodate an abutting engagement thereof with a second, given heat exchanger unit, to facilitate a mounting of such second unit thereupon.

2. A heat exchanger assembly, for use with a gas compressor having external gas ports, comprising:

a base member having a plurality of mounting surfaces; and a plurality of heat exchanger units mounted in abutting engagement with one surface of said plurality of surfaces; wherein

a second surface of said plurality of surfaces is configured to accommodate an abutting engagement thereof with an external wall of a given gas compressor, to facilitate a mounting of said base member to such external wall; and said heat exchanger units of the plurality thereof are spaced-apart from one another and, together with said base member, cooperate to define a chamber therewithin and further including

wall means mounted to and cooperative with said units and said base member to further define said chamber; and single means coupled to said units for forcing a cooling medium both through said units and through said chamber; and

wherein said units have grill means cooperative with said single means to facilitate the forcing of such cooling medium through all of said units simultaneously.

3. The invention, according to claim 2, wherein:

said base member further has

first means for admitting gas into said base member and for conducting such gas through said one surface for transfer of such gas directly into at least one of said units; and

second means for admitting gas from said one unit directly into and through said base member, and through said second surface, for direct transfer of said gas through an external wall of any given, abutting gas compressor via a given gas port of such gas compressor.

4. The invention, according to claim 2, wherein:

said wall means comprises a manifold; and

said manifold is configured to accommodate an abutting engagement thereof with an exterior wall of a given gas compressor and to facilitate a mounting of said manifold to such exterior wall.

5. The invention, according to claim 4, wherein:
said base member further has

first means for admitting gas into said base member and
for conducting such gas through said one surface for
transfer of such gas directly into at least one of said
units; and

second means for admitting gas from said one unit
directly through said one surface for transfer of such
gas into and through said base member, and through
said second surface, for direct transfer of said gas
through an external wall of any given, abutting gas
compressor via a given gas port or such gas compres-
sor.

6. The invention, according to claim 5, wherein:

said manifold has a given aperture formed therein to accom-
modate an abutting, engaged alignment thereof with a
given gas port in said exterior wall of such gas compres-
sor; and

duct means through connecting said given aperture with
said first means to facilitate a transfer of such gas directly
between said given gas port and said aperture, and to said
first means via said duct means.

7. The invention, according to claim 6, wherein:

said manifold has a second aperture formed therein to receive
fluid coolant therethrough from any such gas
compressor abuttingly mounted thereto, said second
aperture opening upon said chamber.

8. The invention, according to claim 7, wherein:

said base member has an aperture formed therein to receive
fluid coolant therethrough from any such gas compressor
abuttingly mounted thereto, said base member aperture
opening on said chamber.

9. In the combination with a gas compressor having a plu-
rality of stage housings with external gas ports, a base for sup-
porting thereon at least one heat exchanger unit, comprising: a
base member having a plurality of mounting surfaces; wherein
at least one of said mounting surfaces is configured to accom-
modate an abutting engagement thereof with at least one
given heat exchanger unit, to facilitate a mounting of such one
unit thereupon; and

a second of said mounting surfaces is in abutting engage-
ment with an external wall of one of said stage housings;
said base member having channeling and tube-end means
for admitting gas into said base member and for conduct-
ing such gas through said one mounting surface for
transfer of such gas directly into any such one given heat
exchanger unit abuttingly engaged therewith; and

port means for admitting gas from such one unit directly
into and through said base member, and through said
second surface, for direct transfer of said gas through an
external wall of said gas compressor via a given gas port
of said compressor;

wherein said base member further includes at least a second
port means for admitting gas directly into said base
member from said compressor, upon such gas issuing
from said gas compressor, through an external wall of
another of said stage housings via one of said gas ports;
and further tube-end means for directly conducting gas
from within said base member through said one mounting
surface of said plurality thereof; and said one mounting
surface is further configured to accommodate an abutting
engagement thereof with a second, given heat exchanger
unit and to facilitate a mounting of such second unit
thereupon; and

wherein said channeling, tube-end, and port means together

comprise a plurality of openings formed in said one sur-
face, and plurality of apertures formed in said second sur-
face, given openings of said plurality thereof facilitating a
conduct of gas through said first surface for conduct of
gas into and out of any given heat exchanger units
abuttingly engaged with said surface, and said plurality of
apertures facilitates a communication of gas between said
base member and given ones of said gas ports.

10. In combination, a gas compressor having a plurality of
stage housings with external gas ports, and a heat exchanger
assembly, comprising:

a first stage housing and a second stage housing, said hous-
ings being coupled together;

a base member having a plurality of mounting surfaces; and
a plurality of heat exchanger units mounted in abutting en-
gagement with one surface of said plurality of said sur-
faces; wherein

a second surface of said plurality of surfaces is in abutting
engagement with an external wall of one of said stage
housings;

said heat exchanger units of the plurality thereof are
spaced-apart from one another, and together with said
base member, cooperate to define a chamber therewithin;
and further including

wall means mounted to and cooperative with said units and
said base member to further define said chamber; and
single means surmounting said chamber for forcing a cool-
ing medium both through said units and through said
chamber.

11. The invention, according to claim 10, wherein:
said units have grill means cooperative with said single
means to facilitate the forcing of such cooling medium
through all of said units simultaneously.

12. The invention, according to claim 10, wherein:
said wall means includes a manifold; and
said manifold is in abutting engagement with an exterior
wall of another of said stage housings.

13. The invention, according to claim 12, wherein:
said base member further has first means for admitting gas
into said base member and for conducting such gas
through said one surface for transfer of such gas directly
into at least one of said units; and

second means for admitting gas from said one unit directly
through said one surface for transfer of such gas into and
through said base member, and through said second sur-
face, for direct transfer of said gas through said external
wall of said one stage housing via a given gas port of said
compressor.

14. The invention according to claim 13, wherein:
said manifold has a first aperture formed therein to accom-
modate an abuttingly engaged alignment thereof with a
given gas port of said compressor in said exterior wall of
said another stage housing; and
duct means through connecting said first aperture with said
first means to facilitate a transfer of such gas directly
between said given gas port and said aperture, and to said
first means via said duct means.

15. The invention, according to claim 14, wherein:
said manifold has a second aperture formed therein to receive
fluid coolant therethrough from said gas compres-
sor, said aperture opening on said chamber.

16. The invention, according to claim 15, wherein:
said base member has an aperture formed therein to receive
fluid coolant therethrough from said gas compressor, said
base member aperture opening on said chamber.
